UNITED STATES PATENT OFFICE.

ELLSWORTH E. FLORA, DECEASED, LATE OF CHICAGO, ILLINOIS; BY LUELLA B. FLORA, EXECUTRIX, OF CHICAGO, ILLINOIS, ASSIGNOR TO CONSOLIDATED STEEL STRAPPING COMPANY, OF CHICAGO, ILLINOIS, A CORPORATION OF DELAWARE.

SEALING TOOL.

Application filed March 4, 1920. Serial No. 363,270.

To all whom it may concern:

Be it known that I, ELLSWORTH E. FLORA, deceased, by Luella B. Flora, executrix, a citizen of the United States, residing at Chicago, in the county of Cook, State of Illinois, have invented an Improvement in Sealing Tools, of which the following is a specification.

This invention relates to tools for forming joints in mutually overlapped ends of flat tensioned metallic box strapping and particularly to an improved means for forming or flattening the top of the type of joint in said box strapping, which is made by crimping the strap edgewise to produce a construction such as shown in the cross section of Fig. 5.

It is an object of the invention to produce an efficient, economical, and simple construction of the character described.

In the drawings:

Fig. 1 is an elevation of the operating parts of a sealing tool in open position, the strap being shown engaged by the tool at the beginning of the operation,

Fig. 2 is an elevation of the tool in its closed position after the joint has been formed,

Fig. 3 is a sectional elevation on the line $\alpha-\alpha$ of Fig. 2,

Fig. 4 is a bottom view of the tool in its open position as shown in Fig. 1, and

Fig. 5 is a cross sectional view of a joint such as formed by the tool.

The sealing tool of this invention is constructed after the manner of a pair of pliers and in its general form is similar to that of the Flora Patent, 1,038,109, dated September 10, 1912, and it makes the same joint.

The improvement consists in a more effective arrangement and simplified construction of the so-called "chair", or piece which forms the top of the crimped joint.

Thus in the drawings, the jaws 1, 1, operated by handles 2, 2, pivoted on the bolt 3, attack the strap (which may be enclosed in a seal as shown) substantially edgewise forming it into the cross sectional configuration shown in Fig. 5. In this operation the lower edges or blades 5 of the jaws pass under the strap, the edges of which are caught in the angle between the forming pins 6 and the upper surface of the blades 5. The strap

is thereby thrown upwardly in the middle, and a joint is formed with hollows in its sides, to fit the faces of the forming pins 6.

It is desirable to form the top of the joint, i. e. to flatten or crush it down, to make the joint as flat on the boxes as practicable. For this purpose I provide a split forming member comprising two halves 7, 7, each formed with a recess 8 so that when the members 7, 7 are in alignment a complete forming surface for the top of the joint will be provided. The bottom of the recesses 8, 8 (which form the top of the joint) are slightly rounded, but substantially flat.

Each of the forming members 7 is provided with an extension 9, pivoted on the bolt 3, sunk into a recess in the outer vertical face or side of the adjacent jaw 1, and held therein by the head 9 and nut 10 on the bolt 3, so that each half of the forming member moves rigidly with the adjacent jaw.

Thus the jaws are opened, (as when applying the tool to the strap), the forming member 7, 7 will be out of line (Fig. 4); when the jaws close on the strap, however, the forming members 7, 7 will move toward alignment (Fig. 4), and by this time the jaws are completely closed. The forming members will present in effect a complete forming surface which flattens and forms the top of the joint (Fig. 2).

The construction herein described eliminates the difficulty in causing an integral forming die or plate to assume the correct relative position to the normal plane of the strap and to the sealing tool. The forming member being divided into two halves, each moving with one of the jaws, necessarily the overlapped portion of the two former (Fig. 4) will be symmetrical with and (considering the forming surfaces to be flat) perpendicular to the median line of the sealer, i. e. the line $\alpha-\alpha$ through the axis of the sealer, in the plane of, and half way between the handles. Inasmuch as the strap is firmly held in the notches 5-5 referred to, and therefore its normal plane is always perpendicular to the same line $\alpha-\alpha$, it follows that the forming surface 8, 8 for the top of the joint, from the time the forming members begin to overlap (Fig. 4) until they come into complete alignment (Fig. 2), will al-

ways be parallel to the normal plane of the strap and thus correctly make a flat topped joint.

Having described my invention, I claim:

- 5 1. A sealing tool for joining metallic strap ends comprising a pair of pivoted jaws, adapted to deflect the edges of superposed strap ends, including a split forming device for forming the top of the resulting deformation in the strap, having two halves each pivoted on the axis of the jaws and moving with the jaws, the halves of said device being arranged to slide past each other so as to provide a complete forming surface when the jaws are closed.
- 10 2. A sealing tool for joining metallic strap ends, comprising a pair of pivoted jaws, adapted to deflect the edges of superposed strap ends, including a split forming device adapted to form the top of the resulting deformation in the strap, said forming device comprising two halves, each pivoted on the axis of one of the jaws and locked against pivotal movement relative to the jaw by a portion extending into a recess in said jaw, said forming device adapted to provide a complete forming surface for the top of the joint.
- 15 3. In apparatus of the class described and in combination, a pair of plier-like jaws, a pivot therefor, a pair of forming devices each adapted to mold one half of the upper side of a strap joint, each of said devices being arranged outside the adjacent jaw, and pivoted on the jaw pivot, and engaged with the jaw by projecting into a recess therein so as to be moved thereby.
- 20 4. In a sealing tool, a pair of plier like jaws, a pivot therefor, a pair of forming devices mounted on said pivot each adapted to form one-half of the upper side of a strap joint, said forming devices being slidible each past the other so that when said jaws are in fully operative position said forming

devices provide a complete forming surface 45 for the top of the joint.

5. In a sealing tool, a pair of plier like jaws, a pivot therefor, a pair of forming devices, each adapted to form one-half of the upper side of a strap joint, each of said devices being pivoted on the jaw pivot and having a part projecting into a recess in the adjacent jaw, said devices being slidible each past the other so that when said jaws are in fully operative position they provide 55 a complete forming surface for the top of the joint.

6. In a sealing tool, a pair of pivoted jaws adapted to deflect the edges of superposed strap ends, a split forming device adapted 60 to form the top of the resulting deformation in the strap, said forming device comprising two halves each mounted on the pivot of the jaws and locked against pivotal movement relative to the jaw by having a portion 65 extending into a recess in the adjacent jaw, the halves of said forming device being slidible each past the other so that when said jaws are in fully operative position said halves provide a complete forming surface of the top of the strap joint. 70

7. In a sealing tool, a pair of plier like jaws, a pivot therefor, a pair of forming devices each adapted to mold one-half of the upper side of a strap joint, said devices 75 being arranged on the opposite sides of said jaws respectively, and pivoted on the jaw pivot, and fixed to the jaw by having a projection extending into a recess in the jaw, said forming devices being slidible each 80 past the other so that when said jaws are in fully operative position said devices provide a complete forming surface for the top of the joint.

In testimony whereof, I have signed my 85 name to this specification.

LUELLA B. FLORA,
Executrix of Ellsworth E. Flora, deceased.
